PUMP

Francis E. Brady, Jr., Connersville, Ind.

Application March 2, 1938, Serial No. 193,416

7 Claims. (Cl. 103—113)

This invention relates to liquid pumps and more particularly to pumps that are adapted to clear themselves from entrapped air or vapor. The present application is a continuation in part 5 of my prior application Serial No. 116,375 filed December 17, 1936.

One object of the invention is the provision of a liquid pump in which air or vapor is withdrawn from the spaces which are in communication with a common inlet passage and which exist between adjacent impeller blades of a centrifugal pump, as the impeller rotates, by a stream of liquid that is forced around the end of a blade and into the space between adjacent blades so as to scavenge air from such space, the vapor and liquid being removed together through the discharge passage of the pump.

Another object of the invention is the provision of a pump of the character mentioned in which the impeller chamber of the pump is arranged horizontally and is provided with an air or vapor collecting portion which conducts the air or vapor to the discharge passage so it will not be returned to the impeller spaces.

Another object of the invention resides in the 25 method of operation of a centrifugal pump adapted to prime itself as above mentioned.

Another object of the invention is the provision of a self-priming pump of the character mentioned and having a priming inlet reservoir which is adapted for connection to a suction pipe and which has a single outlet opening communicating directly with the inlet of the pump, the construction being such that a suitable quantity of liquid is provided in the reservoir so that an effective pumping action will take place after the pump is started and before the liquid is exhausted from the priming reservoir. The latter is sufficiently shallow so that air or vapor will 35 be carried out into the pump by the stream of air which enters the priming reservoir, and when the pump stops the priming reservoir will be 40 full of liquid.

Other objects and advantages of the invention 45 will be apparent from the following description, the appended claims and the accompanying drawings, in which—

Fig. 1 is a vertical central section through a pump embodying the present invention;

Fig. 2 is a horizontal section on the line 2—2 of Fig. 1;

Fig. 3 is a vertical section on line 3—3 of Fig. 2, with the impeller omitted;

Fig. 4 is a vertical section on line 4—4 of Fig. 2, with the impeller omitted;

Fig. 5 is a vertical sectional view of a modified form of the invention; and

Fig. 6 is a section on the line 6—6 of Fig. 4.

Referring more particularly to the drawings by reference numerals, 10 generally designates 5 a pump casing having an inlet passage 11 and an outlet port 12, the latter providing for substantial tangential discharge from the impeller chamber 13. The discharged fluid moves upwardly through the passage 14 into a suitable 10 discharge pipe 15.

Within the impeller chamber 13 which is preferably of generally volute form is an impeller 17, having a series of outwardly extending impeller blades 18. The outer portions of these 15 blades preferably extend rearwardly as indicated in Fig. 2. The spaces between adjacent blades all communicate with the common inlet, which is arranged for axial flow of fluid in a downward direction as shown. The impeller is carried by a vertical impeller shaft 20 which is 20 rotatably mounted in suitable bearings 21 and which is driven by a suitable electric motor 22 or other source of power.

The axial inlet 11 provides the single outlet 25 passage of a priming reservoir 24, which is preferably arranged just above the pump. As shown, the capacity of the priming reservoir is rather large compared with the volume of the impeller chamber of the pump, and the priming chamber 30 moreover, is preferably somewhat wider than it is deep in order that air or vapor will be entrained and carried from the upper portions of the priming chamber in the liquid stream flowing from the suction pipe 26 which extends to 35 a suitable liquid supply. The stream issuing from the pipe 26 impinges on a surface 27 and is thus broken up to more effectively carry along any air or vapor that may be in the upper portion of the reservoir chamber, carrying the same 40 along into the inlet passage 11 of the pump.

The pump is of such character as to handle free air or vapor as well as liquid, and is adapted to prime itself, the rotation of the impeller operating to effectively scavenge the air which 45 is trapped between the blades. When the pump is started, with the priming reservoir 24 full of liquid, and with the pump itself also full of liquid inasmuch as the discharge pipe 15 is at a comparatively high point, the liquid will be 50 drawn into the pump inlet 11 and into the pump from the priming chamber, and if the priming chamber 24 is of such capacity that a replenishing stream of liquid will start to flow from the suction pipe 26 before all the liquid empties 55

- from the priming chamber there will be a continuous stream of liquid entering the pump, this liquid carrying with it any air or vapor that might remain within the priming chamber until the latter is exhausted of air. Thus the priming chamber is promptly filled up and will be full when the pump stops. However, even if the liquid is drawn up in the suction pipe only part way up to the level of the top of the priming chamber at the moment the liquid is exhausted from the priming chamber, the suction will be maintained and increased until liquid does flow into the priming chamber, since the pump is so constructed as to provide a continuous vapor scavenging action by reason of the rotation of the impeller, as will now be described.
- As shown in Fig. 2, the wall of the pump casing, starting at a point adjacent the outlet port 12, curves inwardly and in the direction of rotation and thus provides a surface 30 having a depth substantially equal to the depth of the impeller periphery, and extending inwardly at a substantial angle to a tangent line so as to direct a stream of liquid in the direction of the arrow A and into the body of air or vapor which is trapped between those blades of the impeller which are adjacent or just beyond the outlet port. This stream of liquid is produced by the rotation of the liquid in the impeller volute and by the channel 31 which is more and more restricted up to the point 32 where the wall of the casing is nearest the periphery of the impeller. The rate of flow of liquid in the circulating or volute passage which receives the fluid from the various impeller blades may be less than the lineal speed of the impeller periphery at the outlet port but the speed of the liquid is increased by the channel 31 to exceed the lineal speed of the blade as the jet enters the impeller. The velocity jet or stream of liquid that flows into the space 33, see Fig. 2, breaks through the inner surface of the liquid which may be, for example, at the line indicated by the dash line 34 during the priming operation, and carries into the vapor or air which lies inwardly of the line 34 so that some of the air or vapor which lies inwardly of the line 34 is mixed with or entrained in the stream of liquid breaking into the vapor space. The entrained vapor or air with the broken up or emulsified liquid can thus travel together between the casing and the end of the blade which is just in advance of the point 32 of minimum spacing, as the wall of the casing is suitably spaced from the impeller periphery just beyond the point of minimum spacing between the casing and impeller, so that the velocity jet entering the space 33 is effective in entraining and carrying some air or vapor outwardly of the impeller and into the circulating passage for discharge through the outlet passage 12. Some other portion of the liquid from the volute chamber will flow into the jet creating pocket or channel 31 as the impeller continues its rotation and operate in the manner just described for further priming effect until the gas or air is scavenged out of the pump.
- The air or vapor which is carried outwardly of the periphery of the impeller flows into the upper portion of the start of the horizontal volute or circulating chamber, which is substantially coextensive in depth with the depth of the impeller periphery throughout the extent of the channel 31 and up to the point 39' somewhat beyond the point 32. At the point 39' the volute chamber is extended upwardly as shown at 39, above the level of the top of the ends of the impeller blades.

This upward extension continues around to the outlet. The air or vapor forced or carried outwardly beyond the end of the blade which is in advance of the point of minimum spacing rises into this portion 39 and is retained in the upper part of the volute and flows circumferentially above the level of the impeller periphery to the outlet 12 without returning back into the center of the impeller.

It will be noted that a stream of liquid entering the channel 31 and supplied to the space 33 is substantially free from entrained or mixed air or vapor, since the stream of liquid entering the channel 31 comes from the lowermost portion of the impeller chamber. Any emulsification or mixture of gas or air, and liquid that may be present at the start of the impeller chamber will have had the air or vapor substantially separated from the portion of the liquid in the bottom portion of the impeller chamber by the time it reaches the outlet of the pump, it being noted that the discharge of the air or vapor takes place into the outlet passage at a point above the bottom of the chamber and above the location of the channel 31.

The self-priming as above described is of extreme simplicity and is one in which the stream or jet of liquid entering the space between adjacent blades carries into a space which is in communication with the outlet and with the beginning of the circulating passage or volute chamber of the pump so that there will be a substantial flow at this point. It has been found that it requires only a fractional part of a minute of priming operation before the air or vapor will be practically completely scavenged from the pockets between the blades, and all of the air or vapor will be carried from the priming reservoir 24 into the pump and carried through the pump and discharged through the pipe 15, leaving the pump and the priming chamber both substantially full of liquid. After the pump stops there will then be an adequate supply of liquid in the pump and in the priming reservoir to insure a high degree of suction and proper operation when the pump is again started.

In pumping very heavy or thick oils and the like it has been found that the scavenging of the vapor and liquid combination from the pump chamber is not as rapid as desired in a construction as just described, and for handling materials of this character the modified form of apparatus as shown in Figs. 5 and 6 may be used. In that apparatus the priming chamber 34 and the pump 35 are similar to those previously described except that an additional return line 36 extends from the discharge pipe 37 to a suitable point in the impeller volute spaced a considerable distance from the discharge port 37 so that oil or other similar liquid which is comparatively free from air or vapor is returned back to the impeller chamber and this liquid is then forced into the restricted channel or jet creating pocket 38 and carried inwardly in the direction of rotation between the blades which are adjacent or which have just passed the discharge port 37. The pipe 36 is of limited size so that only a comparatively small portion of the discharged liquid flowing from the pump is returned back to the impeller chamber through this pipe.

While the method and forms of apparatus herein described constitute preferred embodiments of the invention, it is to be understood that the invention is not limited to this precise method and these forms of apparatus, and that changes

may be made therein without departing from the scope of the invention which is defined in the appended claims.

What is claimed is:

5 1. A centrifugal pump comprising a casing providing an inlet passage, an impeller chamber and a peripheral outlet port, an impeller having a series of blades operating in said chamber, said casing having a wall converging toward the impeller periphery from a point adjacent the end of the outlet port and having an inwardly directed terminal surface directing a liquid stream a substantial distance inwardly into the space between adjacent blades and in the general direction of rotation of the impeller, the wall of the casing which defines the outer part of the impeller chamber just beyond said terminal surface in the direction of rotation being located a substantial distance outwardly from the periphery of the impeller so that liquid and gas 10 will be forced outwardly of the impeller periphery from said space when said space receives said stream.

2. A centrifugal pump comprising a casing providing an inlet passage, an impeller chamber and a peripheral outlet port, an impeller rotatable about a vertical axis and having a series of blades operating in said chamber, said chamber having a circulating passage extending around the impeller to the outlet port, said casing having a liquid deflecting surface extending from a point adjacent the outlet port for creating a velocity jet of liquid just beyond the outlet port and substantially at the point of minimum spacing between the blades and the casing and directed inwardly into the space between adjacent blades when the forward end of such space is in free communication with the beginning of said circulating passage and with the inlet passage, said circulating passage having a 15 portion extending upwardly from the periphery of the impeller for conducting gas to said outlet port.

3. A self-priming centrifugal pump comprising a casing having an axial inlet passage adapted for connection to a suction line and having a tangential outlet passage for gas and liquid, an impeller in said casing having fluid impelling blades which drive liquid from the inlet passage to the tangential outlet passage, said casing having a portion providing a circulating passage extending around the impeller to the outlet passage, means for directing a stream of liquid from a point within the casing and in communication with the discharge passage around the end of a blade and in an inward direction for creating, as the rotor operates, a jet of liquid directed inwardly into the space between adjacent blades and in the general direction of rotation of the blades when such space is in free communication with the inlet passage and the circulating passage to combine vapor and liquid and discharge the same together into said circulating passage, and means holding the gas or vapor in the circulating passage to prevent its return from the circulating passage to the impeller.

4. A centrifugal pump comprising a casing providing an axial inlet passage, an impeller chamber and a peripheral outlet port, an impeller having a series of blades operating in said chamber, said casing having a liquid deflecting sur-

face creating a velocity jet of liquid just beyond the outlet port and just ahead of the point of minimum spacing between the blades and the casing and directed inwardly into the space between adjacent blades when such space is in communication with the inlet passage, said casing providing an air or vapor receiving chamber in communication with the outlet port and arranged to prevent return of gas or vapor to the center of the pump.

5. A centrifugal pump comprising a casing providing an axial inlet passage, a volute chamber and a peripheral outlet port, an impeller having a series of outwardly extending blades providing spaces all communicating with the inlet passage, the casing wall just beyond the outlet port in the direction of rotation providing a velocity jet creating portion at the impeller periphery adapted to direct a jet of liquid inwardly into the space ahead of the blade passing the discharge port for scavenging gas from such space, said volute chamber of the casing being arranged substantially horizontally and having a portion extending around the impeller and above the top of the ends of the impeller blades.

6. A centrifugal pump comprising a casing providing an axial inlet passage, an impeller chamber and a peripheral outlet port, said impeller chamber having a horizontally arranged circulating passage extending around the impeller to said outlet port, an impeller rotatable about a substantially vertical axis having a series of blades operating in said chamber, said casing having a liquid deflecting surface creating a velocity jet of liquid just beyond the outlet port and just ahead of the point of minimum spacing between the blades and the casing and directed inwardly into the space between adjacent blades when such space is in free communication with the beginning of the circulating passage.

7. A centrifugal pump comprising a casing providing an axial inlet passage, an impeller chamber and an outlet port, a priming reservoir of substantial capacity arranged entirely above said chamber and adapted for connection at its upper end to a suction pipe and having at the bottom thereof a single outlet opening communicating only with the inlet passage of the pump, an impeller rotatable on a vertical axis and having a series of blades operating in said impeller chamber and providing spaces all communicating with the inlet passage, said casing providing a horizontally arranged circulating passage extending around the impeller to the outlet port and having means provided just beyond the outlet passage in the direction of rotation for directing liquid from adjacent the outlet port in the form of a jet inwardly into the space between adjacent blades when such space is in communication with the beginning of the circulating passage, the wall of the impeller chamber which defines the outer part thereof just beyond said means in the direction of rotation being located a substantial distance outwardly from the periphery of the impeller so that liquid and gas will be forced outwardly of the impeller periphery from the space between adjacent blades when said space receives said jet.
